COMBINATION SHOESHINE BOX, SHOE
REST, AND BOOTBLACK SEATMichael McCormick, New York, N. Y., assignor
of one-half to George Candler, New York, N. Y.

Application March 25, 1950, Serial No. 151,833

7 Claims. (Cl. 15—265)

1

This invention relates to improvements in equipment for use by bootblacks.

An object of the invention is to provide a novel and improved article of bootblack equipment which is adapted to provide novel support for the shoe being shined, and at the same time provide novel seating support for the bootblack while at work.

Another object of the invention is to provide a novel combination including a bootblack seat forming a part of the shoeshine box, and extensible therefrom for the purpose of seating the bootblack, and retractable with relation to the shoeshine box when not needed for such seating purpose, and also for transportation or storage thereof.

A further object of the invention is to provide a novel form of shoeshine box which includes front and side walls defining an inner chamber for the reception of shoe cleaning and shining equipment, and in which a bootblack seat forms part of the shoeshine box, a major element of the bootblack seat forming a retractable and extensible cover member for the inner chamber of the shoeshine box, so that upon extension of the shoeshine seat to a position for use in seating the bootblack, the cover member is automatically moved out of covering position, exposing the contents of said inner chamber for convenient access by the bootblack, and so that upon retraction of the seat, said inner chamber is covered from view and its contents protected.

Still another object of the invention is to provide novel and improved shoeshine box construction, in which the floor wall of the inner chamber of the shoeshine box is apertured to permit free egress by gravity force, of any dirt, debris, or other foreign substances which might otherwise accumulate therein, making it unnecessary to clean out said inner chamber, the floor being characterized additionally by inherent resiliency and in which positioning and constraining means is disposed upon said floor member to subdivide the area thereof, allocating predetermined areas thereof for occupancy by specified articles of equipment, said positioning and constraining means being adjustable in position to conform to the contours of said equipment, and arranged to protect the same.

Still a further object of the invention is to provide a novel and improved form of shoeshine box and combination bootblack seat, in which a horizontal main seat element is supported at its rearward portion by a substantially vertical wall adapted to engage the ground therebelow when

2

in extended position, the horizontal main seat element being slidably engaged with the shoeshine box at its forward portion for being supported thereat, and includes cam means for elevating the lower extremity of the substantially vertical wall automatically upon movement thereof toward retracted position relative to the shoeshine box.

Still another object of the invention is to provide a novel and improved form of shoeshine box and combination bootblack seat, in which receptacle means is provided in the seat for storage of bootblack equipment, with novel and easy means of access thereto, and in which novel and improved means is provided for supporting a shoe to be worked upon, either in a relatively stationary manner, or by shoe support means which permits the shoe to be supported for universal motion.

20 Other objects and advantages of the invention will become apparent from the following description of a preferred embodiment thereof as illustrated in the accompanying drawings, and in which,

25 Figure 1 is a side elevational view of the combination shoe shine box and seat, with the seat portion retracted inside the main shoe shine box, and illustrating the selection of shoe support elements which can be used thereon.

30 Figure 2 is a side elevational view similar to that of Figure 1, showing the seat portion extended ready for use as a seat.

Figure 3 is a fragmentary side elevation similar to that of Figure 1, but showing my novel and improved shoe support element in position for stationary support of the shoe.

Figure 4 is a sectional elevation of the combination shoe shine box and seat shown in Figure 2.

40 Figure 5 is a sectional plan view taken substantially on line 5—5 of Figure 4.

Figure 6 is a left end elevation of the device shown in Figure 1.

Figure 7 is a right end elevation of the device shown in Figure 1.

Figure 8 is a sectional elevation taken on line 8—8 of Figure 4.

In the use of bootblack equipment, it is of the utmost importance that the bootblack be able to keep with him a complete set of working tools, polishes, cleaners, brushes, cloths, and the like, so that he is prepared to handle any kind of work which may be called for. However, in prior art shoeshine boxes, this has not been possible for a variety of reasons. Thus there has been very

little room to store all this equipment, and it has customarily been thrown in hodge-podge fashion into the open shoeshine box, so that access to any desired part thereof has been difficult, and as a result poor work resulted, and in addition the brushes, daubers, cloths, and other equipment became dirty, and hard to work with. Further, the bootblack has found it necessary to kneel on the bare ground in order to do his work, with consequent exposure to colds, and knee ailments therefrom, and continual discomfort. The present invention eliminates all these and many more objections, making it simple, convenient and comfortable for the bootblack, enabling him to do his best work, and making it simple to reach any desired article of equipment, and making the shoeshine compartments self cleaning.

In order to understand clearly the nature of the invention and the best means for carrying it out, reference may now be had to the drawings, in which like numerals denote similar parts throughout the several views.

As shown, there is a main shoe shine box portion generally indicated at 20, and a main seat portion generally indicated at 22. The main shoe shine box portion 20 includes a forward wall 24 secured at its side edges 26 and 28 to the forward marginal edges 30 and 32 of main side walls 34 and 36 respectively, in any suitable manner, as by nailing, screws, or other means. A reinforcing slat 38 extends right across the lower marginal edge of the forward wall 24, being secured thereto in any suitable manner, as by nailing, screws, or the like, and it is seen that the lower edge of the slat 38, that is as at 40, extends lower than the lower edge of the wall 24. The extended edge portion 40 of the slat 38 overlaps the bottom strut 42, that is the forward edge thereof, the strut 42 being secured right across the underside 46 of the forward wall 24, and across the undersides 48 and 50 of the side walls 34 and 36, being secured thereto in any suitable manner, as by nailing, screws or the like, and aiding in maintaining the square relationship of the parts.

Rubber forward feet 52 are secured to the underside of each end portion of the strut 42 in any suitable manner as by screws, nails, or adhesively, being adapted to support the forward portion resiliently upon the ground or floor. A rearward wall 54 has its vertical edges 56 and 58 secured between the inner edges 60 and 62, respectively, of the side walls 34 and 36, in any suitable manner as by nailing, screws or the like, and thus closes the rear end of the main shoeshine box chamber 64 thus defined by the walls 24, 34, 36 and 54. From Figure 4, it is seen that the upper edge 66 of the wall 54, does not go as high as the upper edges of the walls 24, 34 and 36. This upper edge 66 thus provides support for the portion 68 of the main horizontal seat element 70 when in the extended position shown in Figures 2 and 4.

Side rails 72 and 74 are secured to the inner surfaces of the side walls 34 and 36, by screws 76, their upper edges 78 being disposed substantially below the upper edges 80 of the side walls 34 and 36, and sloping rearwardly downwardly as at 82, forming cam surfaces thereat, for supporting the outer edges 84 and 86 of the member 70 upon the rails, allowing the member 70 to ascend from the level shown in Figure 4, to the level where its lower surface 88 is in contact with the plane upper surfaces 78 of the rails 72, 74 upon retraction of the seat to the left as seen in Figure 4, to the retracted position shown in Fig-

ure 1. This elevates the vertical wall member 90 also, upon such retraction, so that its rubber feet 92 are elevated above the floor, to the positions shown in Figure 1. The reinforcing strut 94 extends right across the lower marginal portion 96 of the wall 90, being secured thereto by nailing, screws or other means, and partly overlying the rubber feet 92. Dragging of the rubber feet 92 upon extension or retraction, is thus substantially eliminated by virtue of the dimensions shown, and the cam surfaces 82.

A corner stud 98 is secured by screws 100 to the seat wall 70, and by screws 102 to rear wall 90, in the manner shown in Figure 4, so as to maintain the members 70 and 90 in perpendicular planes as shown. A partition 104 extends across the front edge of the stud 98, being secured thereto to define a small compartment to receive a wire suede brush 106 disposed therein. Side walls 108 and 110, extend upwardly from the edges of the floor member 70, their forward edges 112 being interconnected by a forward wall 114 secured thereto in any suitable manner and also resting upon and secured to the member 70. A strut 116 extends across the forward portions of the upper edges of the walls 108 and 110 and the top edge of the wall 114, being secured in position by nailing or screws. A closure member 118, covering the balance of the opening in the seat compartment 120, has a strap 122 the opposite ends of which extend through notches formed therein to permit it to fit closely in the position shown. The closure member 118 has divergent slats 124 secured to its underside, the forward ends 126 of the slats extending forwardly underneath the toe strut 116 when in the inserted position, to block withdrawal in an upward direction. Hence, when the lock portions 130 and 132 are in engagement, the cover member 118 is secured against withdrawal. At the same time, however, when the seat portion is in extended position as in Figure 2, the cover 118 may be withdrawn in the direction of the arrow 134, to uncover the chamber 120, affording access to the brushes 136 and polishing cloths 138 stored therein. The cover 118 forms the seat for the bootblack to seat himself while working, and it is seen that its elevation is approximately the same as the sole of the shoe, for best results and comfort.

A strut 144 interconnects the lower edges of the side walls 34 and 36, being secured thereto in any suitable manner, and has rubber feet 146 secured thereto at each end. Supplemental side walls 148 and 150 are secured to the rearward portions of the side walls 34 and 36, extending partly beyond and to the right of the right hand edges thereof, as seen in Figures 4 and 5, and are interconnected at their upper ends by means of a cross piece 152. Reinforcing segments 154 are secured to the inner surfaces of the walls 148 and 150, above the top edges of the side walls 34 and 36.

The leading end 68 of the member 70 is reduced in width as seen in Figure 5, and has an underlying foot 160 which acts as a stop against the top of wall 54, so as to block withdrawal toward the right beyond the position shown in Figure 4. Openings 162 are formed through the member 70, to permit dirt to drop therethrough, for easy cleaning. A top piece 166 is secured across the top of the front wall 24 and the forward portions of the top edges of the side walls 34 and 36, and provides a base for the member which is to support the shoe while be-

ing worked upon by the bootblack. This may be the universal shoe support shown at 170, which is fully described in my copending patent application Serial Number 141,287, filed January 30, 1950 and entitled Automatic Shoe Rest and Support, and which matured into Patent No. 2,639,457 issued May 26, 1953, screws 172 penetrating the base flange thereof and the wall 166 for securing the same in the position shown. This permits the customer to turn his foot in any manner as needed.

Or the type of shoe support shown at 174 may be employed, this having feet 176, secured to a plate 178 by means of screws 180. A rod 182 extends across the bottom of the plate 178, being bent toward its lower surface and secured thereto in spaced relationship by screws 184. The rod 182 can be hooked into the lower hook 188 in the manner of Figure 1, when not in use, the lower edge of the plate resting against the front wall 24. A plug 190 is carried on the undersurface of the plate 178, and is adapted to enter a matching opening 192 formed in the stud 166 to receive the same when placed in the operative position shown in Figure 3, being centered automatically thereby. In that position, Figure 3, the member 170 is not in use, but the rod 182 is now hooked into the upper hook 194 of the hook plate 196 secured on the forward surface 24 of the box. The rest 174 is firmly held in position as in Figure 3, and is quite stable.

A floor member 198 has side laths 200 interconnected by end laths 202 resting on members 42 and 144, and a wide mesh screen sheet 204 overlies and is secured to the laths 200 and 202, overlying the central opening 206 formed therebetween. This thus forms the floor of the main shoeshine compartment and is removable by merely elevating it slightly above the members 42 and 144, and twisting it so that it will clear the opening in the bottom, so that it can be withdrawn right through the bottom of the box if needed. Any dirt that may come into the box will fall right through the wide mesh, and hence it stays clean at all times.

A divider member 210 has end walls 212 interconnected by longitudinal walls 214 and 216, which in turn are interconnected by lateral wall 218. The divider member is movable on the upper surface of the wide mesh floor, and provides compartments for four cans of shoe polish 220, dauber brushes 222, and these are maintained at all times in position for being easily selected as needed and reached. At each end there is space for the shoe dye bottles 224 which may remain in their customary cardboard jackets, and also at the other ends, for the shoe cleaner liquids 226, also in bottles as shown. All parts and pieces are readily accessible, and can be inserted and removed without handling any other elements or equipment, thus keeping it clean, orderly and neat. Further, speed of working is enhanced, since there is no need for searching around for any desired article.

Although I have described the invention in specific terms, it will be understood that various changes may be made in size, shape, materials and arrangement without departing from the spirit and scope of the invention as claimed. It will also be clear that the thickness of strap 122 is exaggerated for clarity, and it is flexibly compressible against 118.

I claim:

1. Bootblack equipment comprising a main 75 second cover means forming a closure for said

housing having a first chamber formed therein, a wall forming a floor of said chamber and being formed with openings to allow dirt in said chamber to fall therethrough by gravity force, said first chamber being adapted for the reception of shoe cleaning and polishing materials, a shoe support means carried by said main housing to support a shoe to be cleaned and shined, said chamber having side walls, rail means engaging portions of said side walls of said first chamber, a cover means slidably engaging said rail means and movable from retracted position when it forms a closure for said first chamber, to extended position when it extends outwardly from said main housing, exposing said first chamber to view, said cover means being adapted to be used as a seat, a cover supporting wall means engaging a rearward portion of said cover means for supporting the same above the floor, said cover means providing support for the seating of a bootblack while shining said shoe.

2. The construction according to claim 1, wherein cam surface means is carried by said rail means, and constructed and arranged to elevate 25 said cover means and seat supporting wall means upon retraction thereof into first chamber closing position.

3. The construction according to claim 1, wherein second chamber means is formed in engagement with said cover means for containing 30 articles for cleaning and polishing shoes, second cover means forming a closure for said second chamber means and forming a seat surface for a bootblack while cleaning and polishing said 35 shoe, whereby, upon extension of said cover means from said first chamber means, uncovering the same, said second cover means may be removed to afford access to said second chamber means, and then replaced to provide seating support surface for said bootblack.

4. The construction according to claim 1, wherein said floor of said chamber is removable therefrom, and wherein floor space allocating and constraining means is provided and carried by 45 said chamber floor wall.

5. Bootblack equipment comprising a main housing having a first chamber formed therein, a wall forming a floor of said chamber and being formed with openings to allow dirt in said chamber to fall therethrough by gravity force, said first chamber being adapted for the reception of shoe cleaning and polishing materials, rail means engaging upper wall portions of said first chamber, a cover means slidably engaging said rail means and movable from retracted position when it forms a closure for said first chamber, to extended position when it extends outwardly from said main housing, exposing said first chamber to view, said cover means being adapted to be used as a seat, a cover supporting wall means engaging a rearward portion of said cover means for supporting the same above the floor, said cover means providing support for the seating of the user while using the device.

6. The construction according to claim 5, wherein cam surface means is carried by said rail means, and constructed and arranged to elevate 60 said cover means and seat supporting wall means upon retraction thereof into first chamber closing position.

7. The construction according to claim 5, wherein second chamber means is formed in engagement with said cover means for containing articles for cleaning and polishing and the like, 70 second cover means forming a closure for said

second chamber means and forming a seat surface for a bootblack or other user while using the same, whereby, upon extension of said cover means from said first chamber means, uncovering the same, said second cover means may be removed to afford access to said second chamber means, and then replaced to provide seating support for said user.
